UNITED STATES PATENT OFFICE.

CHARLES C. WILLIS, OF FRAMINGHAM, MASSACHUSETTS, ASSIGNOR TO DENNISON MANUFACTURING COMPANY, OF BOSTON, MASSACHUSETTS, A CORPORATION OF MASSACHUSETTS.

PAPER-PACKAGE.

1,158,353.

Specification of Letters Patent. Patented Oct. 26, 1915.

Application filed February 20, 1915. Serial No. 9,487.

To all whom it may concern:

Be it known that I, CHARLES C. WILLIS, a citizen of the United States, and resident of Framingham, in the county of Middlesex and State of Massachusetts, have invented 5 new and useful Improvements in Paper-Packages, of which the following is a specification.

My invention relates to a package of 10 paper, and especially a package of paper towels or toilet paper, and consists in the novel form of folded and interlocked sheets by which the package is built up, and from which the sheets are to be withdrawn one 15 at a time.

In the accompanying drawings which illustrate one embodiment of the invention, Figure 1 is a plan view of one of the sheets when unfolded; Fig. 2 is a perspective view 20 of a single sheet when folded; Fig. 3 is a perspective view of a package composed of a number of the sheets; Fig. 4 is a perspective view of several of the interlocked sheets, separated a little to show more clearly their 25 relationship; and Fig. 5 is a vertical cross section of a cabinet containing a package of said paper sheets ready for use.

The sheet of paper, which is preferably a little longer than it is broad, as shown in 30 Fig. 1, is first folded transversely on a middle line *a*, thus forming a doubled or two ply sheet. The two ply sheet is then folded again along two lines, *b* and *c*, at right angles to the transverse fold *a*, to form three 35 sections of substantially identical dimensions, namely, a middle section 2 and two end sections 1 and 3, one at each side of the middle section 2. The end section 1 is folded upwardly on line *b*, and the end 40 section 3 is folded downwardly on line *c*.

The sheets thus folded are assembled and interlocked to form a package with each end section (1 or 3) extending between the opposite end section (3 or 1) and the middle 45 section of the next adjacent sheet or sheets. The method of interlocking the end sections one with another is best shown in Figs. 4 and 5. When thus assembled the sheets form a package indicated as a whole by *P*. 50 Preferably as shown in Fig. 3, the lowermost section 3 is folded upward along the side of the package and all the sheets are held together by suitable straps of paper or bands *d*, which may be readily broken or 55 unfastened when the package is to be used.

A represents a cabinet or case in which the packages are stored for use. The cabinet may be supported in any convenient way as by being fastened to a wall *W*. The front of the cabinet is hinged at *H* and in the bottom adjacent to the movable front wall is a slot *B* through which the downwardly folded section 3 of the lowermost sheet depends. 60

C is a weighted follower resting on the package *P* for holding the stacked sheets flattened and preventing their disarrangement as they are pulled out from the bottom. 65

In storing the package in the cabinet for use, the front of the cabinet is swung open 70 upon the hinge *H* and the package, in the condition shown in Fig. 3, is placed within the cabinet with the side having the upwardly folded section 3 toward the front. The straps or bands *d* are then broken, permitting the said upwardly folded section 3 75 to fall downward and depend from the slot *B*. The cabinet front is then swung back into place and the cabinet and package are ready for use. 80

The user desiring to withdraw a sheet pulls the depending section 3 (Fig. 5) downward from the slot *B*, thereby drawing out the lowermost sheet and with it the downwardly folded section 3 of the next 85 superposed sheet, which is interlocked with the upwardly folded section 1 of the sheet being withdrawn, and follows the latter outward through slot *B*, thus leaving section 3 of the bottom sheet always depending, as 90 shown in Fig. 5.

I claim:

1. A package of paper composed of a plurality of superposed sheets, a portion of the bottom sheet extending upward along 95 the side of the package, and a band detachably to secure said sheets as a whole with said upwardly extending sheet against said side.

2. A package of paper composed of a 100 plurality of interlocked sheets, each sheet being folded to form three sections, namely, a middle section and two end sections, one at each side of the middle section, one end section being folded over upon the middle 105 section in one direction and the other in the opposite direction and each end section extending between the opposite end section and the middle section of the next adjacent sheet or sheets, a portion of the bottom 110

sheet extending upward along the side of the package and a band detachably to secure said sheets as a whole with said upwardly extending sheet against said side.

- 5 3. In combination, a cabinet having a movable front, a slot in its bottom adjacent to said movable front, and a package of paper in said cabinet composed of a plurality of superposed sheets, a portion of
10 the bottom sheet extending upward along

the front side of the package, and a band detachably to secure said sheets as a whole with said upwardly extending sheet against said side.

Signed by me at Framingham, Massachusetts, this 6th day of February, 1915.

CHAS. C. WILLIS.
